HANDLE FOR A CULINARY UTENSIL

John J. Fitzpatrick, Hellam, James E. Hess, Columbia, and Ralph P. Wilton, Wrightsville, Pa., assignors to Wilton Brass Company, Columbia, Pa., a corporation of Pennsylvania

Filed Mar. 15, 1968, Ser. No. 10,996

Term of patent 14 years

Int. Cl. D8—02

U.S. Cl. D44—29

FIG. 1 is a perspective top plan view of a handle for a culinary utensil embodying our design.

FIG. 2 is a side elevation thereof.

FIG. 3 is a bottom plan view thereof.

The fry-pan shown in broken lines in the drawing is for illustrative purposes only.

We claim:

The ornamental design of a handle for a culinary utensil, as shown and described.
